UNITED STATES PATENT OFFICE.

WALTER H. WHITTIER, OF GRAND RAPIDS, MICHIGAN, ASSIGNOR TO GRAND RAPIDS REFRIGERATOR COMPANY, OF GRAND RAPIDS, MICHIGAN, A CORPORATION OF MICHIGAN.

REFRIGERATOR-LINING.

970,672.

Specification of Letters Patent. Patented Sept. 20, 1916.

Application filed February 10, 1910. Serial No. 543,086.

To all whom it may concern:

Be it known that I, WALTER H. WHITTIER, a citizen of the United States of America, residing at Grand Rapids, in the county of Kent and State of Michigan, have invented certain new and useful Improvements in Refrigerator-Linings; and I do hereby declare the following to be a full, clear, and exact description of the invention, such as will enable others skilled in the art to which it appertains to make and use the same.

My invention relates to improvements in refrigerator linings, and its object is to provide an air tight lining that will be practically germ proof, easily cleaned, non-corrosive, and that will fully protect the wood-work from any moisture or vapors from the interior of the refrigerator, and to provide the same with various new and useful features hereinafter more fully described.

My improved lining consists essentially of a sheet metal lining provided with round corners and formed up and welded integral before being inserted in the case and also provided with a coating of suitable enamel to protect the same, the lining of the various chambers which communicate through openings in the partitions being connected by flanges formed integral with the lining, inserted in the openings, and connected by suitable coupling rings, together with shelf supports comprising studs secured by suitable fastenings extending from the outer surface of the lining through the same into the supports, whereby the linings are rendered air tight, germ proof, and easily cleaned. The said fastenings also furnish means for spacing the lining apart from the wood-work, whereby an air space is left therebetween, and in various features of construction and arrangement, as will more fully appear by reference to the accompanying drawings, in which:

Figure 1 is a perspective of a refrigerator having my improved lining therein; Fig. 2 a transverse vertical section of the same; Fig. 3 an enlarged detail in vertical section, illustrating the shelf support; Fig. 4 an elevation of the same shown from the right of Fig. 3; Fig. 5 an enlarged detail illustrating the lining in one of the openings in the vertical wall of the device; Fig. 6 a horizontal section of the same on the line 6—6 of Fig. 5; Fig. 7 a vertical section of the same on the line 7—7 of Fig. 5; Fig. 8 a

vertical section on the line 8—8 of Fig. 9; Fig. 9 a plan showing the parts of the lining relative to the horizontal opening in the bottom of the ice chamber; Fig. 10 a horizontal section of one of the linings before insertion; Fig. 11 a detail showing the upper closure of the same; and, Fig. 12 a vertical section on the line 12—12 of Fig. 11.

Like numbers refer to like parts in all of the figures.

Heretofore in the manufacture of refrigerators having metallic linings, these linings are usually formed with sharp angles and of several sheets, all separately inserted and secured in contact with the walls and partitions of the case and having no adequate means for properly covering the openings through the partitions with metallic protection. My improved lining is adapted to overcome these objections, provides rounded corners, which are easily kept clean and an air tight lining spaced apart from the wood-work, which effectually protects the latter and increases the heat excluding character of the walls.

Referring now to the drawings, 1 represents the outer case of a refrigerator having the usual partitions and shelving therein, the form shown having a middle vertical partition 1^a, and a horizontal partition 1^b in one side forming the bottom of the ice chamber, all of the various chambers being provided with an inner lining 2 of sheet metal suitably enameled to protect the same from corrosion, and each lining being made up integral before insertion, the vertical walls being continuous and provided with rounded corners or angles 2^a to facilitate the cleaning of the same, and the top and bottom plates welded to the vertical walls. In the vertical partition 1^a respectively near the top and bottom are openings 3 and 4, through which the air circulates. In the horizontal partition 1^b is an opening 5 through which the cold air from off the ice flows downward and on which partition the water from the melting ice accumulates and flows to the drain pipe. In the linings adjacent to the partition 1^a are openings corresponding to the openings 3 and 4, and integral outwardly turned flanges 6 are formed surrounding these openings and adapted to freely enter the openings of the partition. The edges of these flanges are spaced apart when in place, sufficient to

permit projecting members or pins 9 on the outside of the coupling rings 7 to extend therebetween, and thus retain the rings in place within the flanges and covering the spaces between the same. These coupling rings are preferably made of half round material with the flat side contacting the flanges. They thus afford smooth rounded surfaces, which are easily kept clean and free from any impurities or germs. They also effectually cover and protect the wood-work around the openings. These preferred rings are formed of half round bar and the ends joined by means of circular heads 13 on one end, fitted within corresponding openings on the other end, whereby the ends are interlocked. To prevent water from flowing into the opening 5, the lining of the bottom of the ice box instead of being flanged downward, is flanged upward, whereby a dam is formed around the opening 5, as at 6^a, and the modified coupling ring 8 formed of sheet metal is inserted in the opening and extends downward within the flanges with its upper edge turned outward and downward over the flange 6^a, whereby a smooth and rounded upper edge is formed around said opening. It will be noted that all of these parts are substantially air tight and the wood-work effectually covered thereby.

To avoid any leakage of air through the linings, and to furnish a smooth and easily cleaned support for the shelves, I provide supports preferably in the form of cylindrical bodies having rounded inner ends as at 10. These supports are mounted with their outer ends against the lining and preferably provided with a washer, being held in place by a screw 11 extending through the lining from the outer side, whereby a smooth close fitting support is formed for the shelf, and the screw head (preferably of round head) projecting from the surface of the lining, spaces the same apart from the partitions or wood-work of the case and thus provides a thin air space therebetween, which aids in excluding the heat from the interior of the refrigerator, and also more fully prevents the wood from becoming decayed by moisture or contact with the metal.

By the construction shown, a series of chambers may be connected by an air tight lining, if preferred to extend or enlarge a refrigerator.

The described construction of sheet metal lining by welding in the top and bottom and forming integral flanges, is not herein claimed, but is reserved for a separate application in conformity with requirement of division.

What I claim is:—

1. A refrigerator, comprising a case, a

partition in the case having an opening, a lining at each side of the partition, a flange 65 on each lining extending within said opening, and a coupling ring in the opening covering the seam between the flanges.

2. A refrigerator, comprising a case, a partition in the case having an opening, a lining at each side of the opening, integral flanges on the linings extending within the opening and spaced apart at the edges, a coupling ring engaging the flanges, and an outwardly projecting member on the ring 75 extending between the flanges to hold the ring in place.

3. A refrigerator, comprising a partition provided with an opening, a sheet metal lining at each side of the partition, integral 80 flanges on the linings extending oppositely within the opening, a half round coupling ring having its flat side engaging the flanges and covering the seam therebetween, and outwardly projecting pins in the ring extending between the flanges.

4. In a refrigerator, a bottom to the ice box having an opening, a lining to the bottom, an upturned flange on the lining surrounding said opening, and a ring in said 90 opening having its upper edge turned outward and downward over the upper edge of the flange.

5. A refrigerator, comprising a case, a partition in the case having openings, a 95 sheet metal lining formed integral for each compartment and also having rounded corners, and integral flanges on the lining extending within said openings.

6. A refrigerator, comprising a case, a partition in the case having openings, a sheet metal lining at each side of the partition formed integral and having rounded corners, flanges on said linings extending within said openings, and coupling rings in 105 the openings covering the seams between the flanges.

7. A refrigerator, comprising a case, a lining in the case and spaced apart from the same, a shelf support projecting inward 110 from the lining and engaging the inner surface of the same, and a fastening extending through the lining and into the support and having a head between the lining and case 115 spacing the same apart.

8. In a refrigerator, a lining having an opening, a shelf support engaging the lining at one end and covering said opening, and a fastener inserted through said opening and within the support.

In testimony whereof I affix my signature in presence of two witnesses:

WALTER H. WHITTIER.
